**METHOD OF MANUFACTURING PRINTING PLATES
HAVING A REPLICA PATTERN**

This invention relates to a printing plate for use in impressing a replica pattern on the surface of a thin plate made of paper, cloth or synthetic resin, particularly to a method of manufacturing such printing plates and also decorative plates on which a replica pattern is made clear.

Of the accompanying drawings, FIG. 1a is a perspective view in part of a prototype of wood plate showing its grain on the surface. FIG. 1b is a perspective view in part of a prototype plate made of a deformable material and copied from said prototype, on which the pattern of FIG. 1a is fixed. FIG. 2 is a perspective view in part of a sheet of paper or thin plate on which the pattern of the prototype of FIG. 1a is already fixed. FIG. 3 is a side view of a shade concentrating procedure to spray a coloring matter onto said prototype plate from a direction of an acute angle said prototype plate consisting of a thin plate on which a rugged surface pattern is already copied from said prototype. FIG. 4 is a perspective view of the shade-concentrated prototype plate. FIG. 5 is a perspective view in part of a photographic printing plate as a photographic sensitive plate on which a pattern of shade is photographed. FIG. 6 is a perspective view in part of a gelatinous film on which a pattern of shade is printed. FIG. 7a is a side view in part of a condition wherein a gelatinous film is pasted to the external circumference of a roll. FIG. 7b is a side view, broken in part, of a condition wherein a gelatinous film is pasted to a flat base plate. FIG. 8a is a perspective view in part of a printing roll provided with a replica pattern. FIG. 8b is a perspective view in part of a printing plate provided with a replica pattern. FIG. 9 is a perspective view of a decorative plate having a replica pattern copied from the printing plate shown in FIGS. 8a and 8b.

In order to develop a replica pattern on the surface of a flat plate, heretofore, it has been customary to make a photographic printing plate directly from a prototype by photographic means, on which a desired pattern has been carved or molded. According to this usual procedure, it is almost impossible to make a clear-cut rugged surface shade and to obtain a satisfactory printing plate with a replica pattern sufficiently resembling the prototype with the only result that a poor replica and flat-looking pattern may be obtained at best.

In contrast, according to the present invention, it is possible to overcome such drawback as mentioned above and to make clear even the slightest extent of rugged surface pattern of any prototype by extremely simple means. Namely, the object of the present invention consists in easily and economically obtaining decorative plates by making a particularly emphasized replica pattern on any flat-surface plate suitable for manufacturing such decorative plates having a sufficient, replica pattern and thus ensuring a method for manufacturing such printing plate as has been described hereinbefore.

The method of the present invention is thus characterized by the fact that a prototype in the form of a natural object or a copy thereof having a desired pattern of uneven surface is overlaid on a thin deformable material made of, for example, paper, cloth or synthetic resin for transferring the replica pattern of the prototype onto said deformable material to form it into a prototype plate and then a coloring matter is sprayed onto its surface from a direction of an acute angle greater than 0° but less than 90° to make a dark-shade portion on the side directly confronting said spraying direction and to make the other side a light-shade portion, thereby embossing the uneven surface pattern of the prototype plate for better emphasis of said replica pattern and then the prototype plate thus treated is photographed on a sensitive plate to produce a photographic printing plate, thereby permitting the simple and economical mass production of decorative plates made of paper, cloth or synthetic resin, having a clear shaded pattern developed by said printing means.

The invention will be explained in detail with reference to the accompanying drawings.

A plate of wood with its outstanding grain (e.g. in weather-beaten condition until its annual rings are clearly exposed) is

used as a prototype 1 with a solid pattern 2 on which is overlaid a thin plate 3 made of paper or a shapeable, namely, deformable material in such a manner that the replica pattern 2 of grain of wood can be transferred to the thin plate 3 by sliding after pressing thereon, like relief copying, to form a prototype plate 3' provided with a rugged surface pattern 2'. Then, as shown in FIG. 3, the required coloring matter is sprayed onto the surface of the prototype plate 3' by means of a sprayer 4 from a direction of an acute angle so that there is formed a prototype plate 3'' of shade type, having a dark-shade portion 5 and a light-shade portion 6 corresponding to the dark and light shades of the rugged surface pattern 2', and the dark shade portion 5 and light shade portion 6 on the prototype plate 3'' are photographed on a sensitive plate by usual photographic means, the image of which is then developed and fixed suitably, thereby producing a photographic printing plate 7, chemically stabilized and showing a light shade image 5' and a dark shade image 6'. Subsequently, the photographic printing plate 7 is closely secured to a gelatinous film 8 cemented with a base sheet of paper 9 for ultraviolet ray printing purposes so that it is rendered possible to harden only those areas having been exposed to ultraviolet ray on reaction with potassium bichromate mixed in the gelatinous film 8. Namely, because of ultraviolet ray printing of network type on the gelatinous film 8 beforehand, those portions thereof corresponding to light and dark shade gradation of the photographic printing plate 7 are sure to become hardened by order of said network units, thus forming hardened portions 5'' and 6'' thereon respectively. While the film 8 cannot be discerned by the sense of sight, the hardened portions 5'' and 6'' shown in FIG. 6 are intentionally emphasized in expression for better clarification.

As the next procedure shown in FIGS. 7a and 7b the gelatinous film 8 with said printed pattern is closely pasted to an etch-workable metal 10 like copper plating or a metal with the same etch-workable effect as copper and then the base sheet of paper 9 is stripped off the gelatinous film 8 by water application. Then an etching solution composed of ferric chloride ($FeCl_3$) is repeatedly applied to the gelatinous film 8 on the surface of the etch-workable metal 10 whereby the gelatinous film 8 can be dissolved little by little starting from such area as has not been sufficiently hardened during exposure to ultraviolet ray, until the etching solution reaches the surface of the etch-workable metal 10 from which part the etching action starts to work thereby developing a light and dark shade expression depending on the difference of etching time and providing a printing roll 12 or a flat printing plate 14 formed with a replica pattern 10'. As has been described hereinbefore, in case the pattern of the prototype is not of a sufficiently uneven surface, a sheet of paper or thin deformable material 3 is overlaid directly on the original prototype 1 to form a pattern of uneven surface like relief copying or the replica pattern 2 of the prototype may be formed on gypsum or any similar deformable material for use as a copied prototype 1' on which a sheet of paper or thin deformable material 3 may be overlaid to produce the prototype plate 3' formed with said pattern of uneven surface as by the above mentioned method of relief copying in a simple and exact manner capable of copying a pattern of uneven surface from a prototype.

Moreover, it is also possible to produce the prototype plate 3' by push-pressing a sheet of paper or thin deformable material of synthetic resin by insertion between a male mold and a female mold in which the required pattern is carved or molded by some suitable means or other. In this case, especially when the pattern is of a geometrically solid carving type, the preparation of a male and a female mold for such a purpose will be easy and all the more convenient for use.

Consequently, as explained before, it is possible to manufacture a printing plate with an emphasized shade pattern from the prototype plate 3' in an extremely simple manner by forming on paper or a plastic plate a replica pattern resembling a natural object or a model copied from it by suitable means.

According to the method of the present invention for manufacturing printing plates, even in case the uneven surface of any prototype is insufficient in appearance, a coloring matter can be used for better emphasis of a light and dark shade proportion for obtaining a photographic printing plate by the usual photographic means in a manner emphatically resembling the light and dark shade proportion of said uneven surface pattern, and therefore this photographic printing plate can be installed on an ordinary printing machine, for example, a roller-type or flat-plate printing machine so as to permit the manufacture of a decorative plate 15 with an emphasized replica pattern, made of paper, cloth or synthetic resin as shown in FIG. 9.

The decorative plate 15 thus obtained is sure not only to show a distinctive light and dark shade in its lightfaced or shade position but also to give an embossed replica with an emphasized shade tone due to the fact that the effect of the required coloring matter in the intermediate portions is likely to change little by little. What is more, even in case the prototype is found to be a poor replica at first, its shade can be emphasized by the use of such coloring matter as mentioned above during the manufacturing procedures of printing plates so that it is rendered possible to intensify such shade and thereby improve the replica.

Thus, decorative plates of the type described can be applied to house walls, ceilings, surfaces of other structures, furniture, instruments, etc., in a manner with the intended characteristics of the present invention for manufacturing such decorative plates easily and economically.

Although the presently preferred embodiment of the present invention has been explained, with reference to the accompanying drawings, it is not intended that the present in-

vention be restricted to said embodiment and various modifications or improvements are also available without departing from the scope of application for patent as shown in the appended claims.

What is claimed is:

1. A method of manufacturing printing plates with a replica pattern comprising forming a prototype plate in the form of a thin plate with a rugged-surface pattern from a prototype, forming a light- and dark-shade tone on said prototype plate by spraying a coloring matter onto said prototype plate from a direction of an acute angle, photographing said prototype thus formed with said light- and dark-shade tone to make a photographic printing plate, printing the light and dark shade of said photographic printing plate on a gelatinous film by exposure to ultraviolet ray, pasting said gelatinous film to an etch-workable metal and bringing an etching solution into contact with said gelatinous film thereby forming said pattern of prototype on the surface of said etch-workable metal by etching means.
- 10 2. A method according to claim 1, said thin plate being made of paper.
- 15 3. A method according to claim 1, said thin plate being made of synthetic resin.
4. A method according to claim 1, wherein a rugged surface pattern is copied from a natural object onto a deformable material for use as a prototype.
- 20 5. A method according to claim 1 wherein a natural object is used as a prototype.
- 25 6. A method according to claim 1 wherein said prototype plate is obtained by molding between a male mold and a female mold.
